UNITED STATES PATENT OFFICE.

MAGNUS NELSON, OF MARINE MILLS, MINNESOTA.

CYLINDRICAL TUBE FOR USE IN WALLING UP WELLS WITH CONCRETE, CEMENT, &c.

SPECIFICATION forming part of Letters Patent No. 249,389, dated November 8, 1881.
Application filed July 5, 1881. (Model.)

To all whom it may concern:

Be it known that I, MAGNUS NELSON, of Marine Mills, in the county of Washington and State of Minnesota, have invented a new and useful Improvement in Formers for Use in Cementing Wells; and I do hereby declare that the following is a full, clear, and exact description of the same.

Where the earth is sufficiently solid and compact it is preferable, as a matter of economy, to apply cement to the sides of wells, in place of employing brick or stone, to form a wall around the same. I have devised an improved collapsible former for use in such application of cement. The same is shown in accompanying drawings, in which—

Figure 1 is a sectional elevation, and Fig. 2 a plan view.

The former is cylindrical in shape, and its body is mainly constructed of a series of longitudinal parallel strips or staves, *a*, each of which is segmental in cross-section. The staves are suitably secured to two transversely-divided steel bands, *b b*, which are arranged, one near each end of the former, on the inner side thereof.

A narrow iron plate, *f*, having the same length as the staves *a*, is rigidly attached to the outer side of the stave, on one end of the bands *b*, so that it overlaps the contiguous stave on the other and opposite ends of said bands.

To hold the former rigid, as required, during the operation of applying the cement, as hereinafter described, I employ slotted hasps *c* and pivoted hooks *e*, that respectively fit over and enter staples *d*, these devices being applied to the ends of the bands *b*, so as to connect them, as shown.

For the purpose of lowering or hoisting the former in the well a rope, *g*, is attached to its upper portion. I propose to use a series of such formers, the number being more or less,

according to the depth of the well. They are connected and held rigidly in position by lugs *h*, that project from the lower end of each former 45 and enter keepers on the upper end of the one below it.

The operation of the device is as follows: one section of the tube is placed in the well, upon the bottom thereof, and the space between the tube and the sides of the well filled with cement; then another section is placed on the top of the first, and the space between it and the sides of the well filled up in like manner; then another section, and so on until 55 the surface of the ground is reached, and a continuous wall of cement is formed between said tube and the sides of the well, and when the cement is sufficiently set and firm the hasps of the upper section of the tube are removed 60 and the latter drawn out of the well by means of the rope passed through the loops in the band of said section, as aforesaid, and the other sections of the tube removed in the same way.

I am aware a collapsible former has been 65 provided with racks and pinions for adjusting their diameter as required in the operation of cementing wells, and I do not claim such device *per se*.

What I claim is—

1. The collapsible former provided with lugs *h*, attached to its lower end, and with keepers on its upper end, as shown and described, for the purpose of connecting a series of formers, as specified.

2. The combination, with the former constructed of vertical staves *a*, the divided bands *b*, and plate *f*, of the fastenings consisting of the hook and hasps *c*, arranged as shown and described.

MAGNUS NELSON.
